(57) CLAIM

A design for a nippled top for a baby bottle, as shown and described.

DESCRIPTION

FIG. 1 is a top front right perspective view of a nippled top for a baby bottle, showing our new design in a condition of use;

FIG. 2 is a front elevational view thereof;

FIG. 3 is a top plan view thereof; and,

FIG. 4 is a bottom plan view thereof.

The broken line showing of a baby bottle in the drawings represents unclaimed environmental subject matter and forms no part of the claimed design.
